V. A. DANIEL

Des. 147,535

BOUTONNIERE

Filed May 21, 1946

FIG. 1.

FIG. 2.

VADA ALICE DANIEL
INVENTOR.

BY Cecil P. Hood

ATTORNEY

UNITED STATES PATENT OFFICE

147,535

DESIGN FOR A BOUTONNIERE

Vada Alice Daniel, Fort Worth, Tex.

Application May 21, 1946, Serial No. 129,927

Term of patent 14 years

(Cl. D29—1)

To all whom it may concern:

Be it known that I, Vada Alice Daniel, a citizen of the United States of America, residing at Fort Worth, in the county of Tarrant and State of Texas, have invented a new, original, and ornamental Design for a Boutonniere, of which the following is a specification, reference being had to the accompanying drawing, forming part thereof.

Figure 1 is a front elevational view of a boutonniere showing my new design, and

I claim:

The ornamental design for a boutonniere, substantially as shown.

VADA ALICE DANIEL.
